UNITED STATES PATENT OFFICE

2,530,088

GOLF TEE

Charlie William Smith, St. Louis, Mo.

Application August 12, 1949, Serial No. 109,863

6 Claims. (Cl. 273—33)

1

The present invention relates to golf tees and it consists in the combinations, constructions and arrangements of parts herein described and claimed.

Generally there is provided a golf tee which is formed of a single piece of paper or the like and which is provided with a wire reinforcement. The device is so folded as to present a ball-holding member, a relatively long flat leg and a relatively short flat leg. By means of the embedded wire the legs may be quickly and easily positioned to meet varying conditions of terrain and the ball supporting member may be bent to a vertical position regardless of the position of the two leg members. Novel means is provided for supporting the ball upon the ball holding member.

It is accordingly an object of the invention to provide a device of the character set forth which is exceedingly simple in construction, inexpensive to manufacture and yet effective and efficient in use.

Another object of the invention is the provision of novel means, in a device of the character set forth, for positioning and maintaining in position a pair of legs forming a part of the invention.

Another object of the invention is the provision of novel means for supporting a ball upon a support member forming a part of the invention.

A further object of the invention is the provision of a device of the character set forth which will be safe to carry.

Another object of the invention is the provision of a golf tee which will support a golf ball without the necessity of becoming embedded in the ground as is the conventional tee.

A still further object of the invention is the provision of a device of the character set forth which may easily be found after being accidentally struck when driving at a golf ball which may be mounted thereon.

Other and further objects of the invention will become apparent from a reading of the following specification taken in conjunction with the drawing, in which:

Figure 1 is an elevational view of an embodiment of the invention,

Figure 2 is a side elevational view thereof shown in a position where a golf ball is supported at medium height from the ground,

Figure 3 is a plan view of the device shown in Figure 1,

Figure 4 is a perspective view of the device,

2

Figure 5 is a vertical sectional view illustrating one form of construction,

Figure 6 is a view similar to Figure 2 but showing the device supporting a ball at a relatively lower position with regard to the ground,

Figure 7 is a view similar to Figure 6 but showing the device as used when it is desired to have the ball at a very lowered position with regard to the ground,

10 Figure 8 is a view similar to Figure 2, 6 and 7 but showing the device as used when it is desired to elevate the golf ball at a maximum distance from the ground,

15 Figure 9 is a vertical sectional view of the device illustrating another form of construction, and

Figure 10 is a perspective view of a wire reinforcement device as utilized in the construction shown in Figure 9.

20 Referring more particularly to the drawing, there is shown therein a body 10 of cardboard or the like, the free ends of which are brought together and folded inwardly, as indicated at 11, to form a ball support 12. A portion of the body 10 is folded upon itself, as indicated at 13, to form a relatively short leg 14 and another portion is folded upon itself, as indicated at 15, to form a relatively long leg 16.

The elements forming the support 12 are 30 fastened together by means of staples 17 which are driven therethrough adjacent the side edges thereof and to form a more secure support for a golf ball 18, and the upper edges of the support 12 may be pulled apart to form supporting lips as indicated at 19 in, for example, Figure 4 of the drawing.

A reinforcing and holding member 20, preferably formed of bendable wire, is centrally disposed between the folds of the legs 14 and 16 and, 40 in the form of the invention shown in Figure 5, for example, this member does not extend into the support 12.

In the form of the invention shown in Figures 9 and 10 the construction above referred to is 45 identical with the exception that instead of the member 20 a wire 21 has its free ends 22 mounted within the folds of the members 11 and has looped portions 23 and 24 mounted within the folds of the legs 14 and 16, respectively.

50 In operation, it will be apparent that due to the bendable members 20 and 21 the support member 12 and the legs 14 and 16 in either form of the invention may be bent to assume an infinite variety of relative positions so that the ball 55 18 may be supported at a relatively lower posi-

tion with regard to the ground, as shown in Figure 7, a relatively high position with regard to the ground as disclosed in Figure 8, a medium position with regard to the ground as disclosed in Figure 4 or may support a ball upon an inclined surface as clearly shown in Figure 6.

It will be understood that the outer surface of the device may be imprinted with advertising matter or other data and that the outer side of the device may be brilliantly colored so that the same may be located easily in the event that it is struck during a drive.

While but two forms of the invention have been shown and described herein, it will be readily apparent to those skilled in the art that many minor modifications may be made without departing from the spirit of the invention or the scope of the appended claims.

What is claimed is:

1. A device of the character described comprising a body formed of flexible material folded to form a ball-supporting member and a pair of legs and a bracing member of bendable material embedded in the folds of the leg members.

2. A device of the character described comprising a body formed of a single piece of flexible material folded to form a ball-supporting member and a pair of legs and a bracing member of bendable material embedded in the folds of the leg members.

3. A device of the character described comprising a body formed of a single piece of flexible material folded to form a pair of legs and a ball-supporting member and a bracing member formed of a single piece of bendable material and extending between the folds of the supporting member and each of the legs.

15

5

4. A device of the character described comprising a body formed of a single piece of flexible material folded to form a relatively long leg, a relatively short leg and a ball supporting member and a bracing member formed of a single piece of bendable material and extending between the folds of the supporting member and each of the legs.

5. A device of the character described comprising a body of flexible material folded to form a ball-supporting member, a relatively long leg and a relatively short leg and a bracing member of bendable material embedded in the folds of the leg members.

6. A device of the character described comprising a body formed of a single piece of flexible material folded to form a relatively long leg, a relatively short leg and a ball-supporting member, a bracing member formed of a single piece of bendable material and extending between the folds of the supporting member and each of the legs and a pair of outwardly extending lips formed in the upper end of the supporting member.
